(57) **CLAIM**

The ornamental design for a display screen or a portion thereof with graphical user interface, as shown and described.

DESCRIPTION

FIG. 1 is a front view of an image of a graphical user interface for a display screen or a portion thereof according to our design, shown in a first embodiment; and, FIG. 2 is a front view thereof in a second embodiment. The broken line showings of portions of a display screen in the figures are environmental only and form no part of the claimed design. The areas including stipple-fill show a portion of the design that has a contrasting appearance to the non-filled areas.
